Primary Examiner — Ricky Pham(74) *Attorney, Agent, or Firm* — Abelman, Frayne & Schwab(57) **CLAIM**

The ornamental design for a baking dish, as shown and described.

DESCRIPTION

FIG. 1 is a top, front and left side perspective view of the baking dish of my new design;

FIG. 2 is a front elevation view thereof, the rear elevation being a mirror image;

FIG. 3 is a left side elevation view thereof, the right side elevation being a mirror image thereof;

FIG. 4 is a top view thereof; and,

FIG. 5 is a cross-section taken along line 5-5 of FIG. 4.

1 Claim, 5 Drawing Sheets*FIG. 1*

FIG. 2

FIG. 3

FIG. 4
